(57) **CLAIM**

We claim the ornamental design for a reconfigurable center floor console for an automotive vehicle, as shown and described.

DESCRIPTION

FIG. 1 is a rear-perspective view of a reconfigurable center floor console for an automotive vehicle, of the new design; FIG. 2 is a front-perspective view thereof; FIG. 3 is a side view thereof; FIG. 4 is a top view thereof; FIG. 5 is a side view thereof, opposite that of FIG. 3; FIG. 6 is a top view thereof with a generally transparent sliding door in an open position; FIG. 7 is a rear-perspective view thereof with the sliding door in the open position; FIG. 8 is a rear-perspective view thereof with the sliding door in the open position and a cup holder in a forwardly advanced position; FIG. 9 is a side view thereof with an arm rest in a raised position; and, FIG. 10 is a rear-perspective view thereof with the arm rest in the raised position.

The broken lines are for environmental illustrative purposes only and form no part of the claimed design. The broken shading on the generally horizontal sliding door surface indicates transparency.
